UNITED STATES PATENT OFFICE.

MORRIS KASSMAYER, OF NEW YORK, N. Y., ASSIGNOR, BY DIRECT AND MESNE ASSIGNMENTS, OF ONE-HALF TO JOHAN DOHNAL AND SIGMUND COHN, OF SAME PLACE.

FOLDING TOP FOR VEHICLES.

SPECIFICATION forming part of Letters Patent No. 600,724, dated March 15, 1898.

Application filed December 14, 1897. Serial No. 661,831. (No model.)

To all whom it may concern:

Be it known that I, MORRIS KASSMAYER, a subject of the Emperor of Austria, residing in New York city, in the county and State of 5 New York, have invented a new and Improved Folding Top for Vehicles, of which the following is a full, clear, and exact description.

The object of the invention is to provide a new and improved vehicle folding top arranged to permit the occupant of the vehicle to conveniently and quickly raise or lower the top without leaving the seat, the top when lowered being completely folded within the seat-casing.

15 The invention consists of novel features and parts and combinations of the same, as will be fully described hereinafter, and pointed out in the claims.

Reference is to be had to the accompanying 20 drawings, forming a part of this specification, in which similar characters of reference indicate corresponding parts in all the figures.

Figure 1 is a sectional side elevation of the improvement as applied and folded up and 25 with the seat proper removed. Fig. 2 is a like view of the same on the line 2 2 of Fig. 3 and showing the top extended. Fig. 3 is a transverse section of the improvement on the line 3 3 of Fig. 2. Fig. 4 is an enlarged edge 30 view of part of the actuating mechanism, and Fig. 5 is a side elevation of the same.

On the vehicle-body A is held a seat B, formed with a base B' and an outward casing B², which extends a suitable distance upward 35 and follows approximately the outlines of the usual seat. Within the casing B² is adapted to fold the top C from above when not in use, as indicated in Fig. 1. The base B' of the seat supports brackets B³ for the seat B⁴ proper, 40 and in the rear of the said brackets are guide-arms B⁵, between which and the inner surface of the casing folds the top C, so that the latter does not come in contact with the occupants on the seat. The top C is made with a lower 45 folding section C', a middle non-collapsible section C², and an upper or top section C³, having an extension section or hood C⁴, which may or may not be used.

The rigid non-collapsible section C² is provided with two end bows C⁵ and a middle

bow C⁶, attached to brackets C⁷, secured to the ends of the bows C⁵, to form the bows for this section into a rigid frame, covered in the usual manner by a fabric or other suitable material. The ends of the bows C⁵ are fulcrumed on pivots D, extending outwardly from vertically-disposed bars E, fitted to slide in the sides of the base of the seat B, the lower ends of the bars being arranged to pass down through apertures in the bottom 55 of the vehicle-body when the top C is folded up in the seat, as shown in Fig. 1.

The lower ends of the bars E are formed into racks E' in mesh with gear-wheels F, secured on a transversely-extending shaft F', 65 journaled in suitable bearings attached to the base B', and on the said shaft F is secured a bevel gear-wheel F² in mesh with a bevel gear-wheel F³, attached to a longitudinally-extending shaft F⁴, likewise mounted to turn in suitable bearings attached to the base B'. The outer square end of the shaft F⁴ is adapted to receive a crank F⁵ under the control of the operator for turning the said shaft F⁴ and causing the bevel gear-wheels F³ F² to rotate 70 the shaft F', which by the gear-wheels F meshing into the racks E' causes an up and down sliding of the bars E, according to the direction in which the crank-arm F⁵ is turned.

The top section C³ is likewise made non-collapsible, but is fitted to slide over the upper portion of the non-collapsible section C', as indicated in Fig. 1, and this top section C³ is provided with bows C⁸, secured at their ends on collars G, mounted to turn loosely on the 80 pivots D.

Each of the collars G is provided with a crank-arm G', pivotally connected with a rod G², extending downwardly and carrying near its lower end a nut G³, adapted to abut against 85 the under side of a bearing G⁴ for the lower end of the rod G² to limit the upward movement of the latter at the time the bars E move into an uppermost position.

Now it is evident that when the bars E are 90 raised, as previously explained, the several sections of the top are carried upward with the said bars, and when the nuts G³ of the rods G² move in contact with the bearings G⁴ then a swinging motion is given to the crank- 95 100

- arm G', the collar G, and the bows C⁸ upon the farther upward movement of the bars E, so that the top section C³ is caused to swing forward to uncover the upper part of the section C' and to impart a swinging motion to the latter by a flexible connection C¹⁰, reaching from the forward bow C⁸ to the uppermost bow C⁵ of the section C', as will be readily understood by reference to Fig. 2.
- 10 The outermost bows C⁸ of the top section C³ are rigidly connected with each other by a fixed arm C⁹ to prevent the section from collapsing. The hood C⁴ is collapsible, and its parts are adapted to be held in a stretched 15 position by the usual locking-links C¹¹, connecting the outermost bow C⁸ with the outermost bow C¹² of the hood or extension-section C⁴. This hood may be used or not, as previously explained, and it is drawn out by 20 hand from the end of the section C³ and locked in place by the links C¹¹, as before mentioned. The bows C¹² of this extension-section or hood are mounted to swing loosely on the pivots D.
- 25 The forward end of the hood is provided with a flange C³ for covering the folded section within the box-casing B² when the top is folded therein, as shown in Fig. 1, and the sides of the extension C⁴ are formed with flaps C¹⁴ for covering up the pivots D and the parts 30 connected therewith at the upper ends of the bars E. (See Figs. 1 and 3.)
- It is understood that the bows C⁸ and C¹² are covered with the usual material to complete the top.
- 35 When the bars E have moved into an uppermost position and the top has been extended, as described and shown in Fig. 2, then a snap-bolt H, carried in one side of the seat-frame B², engages an aperture in one of the bars E to lock the latter in place to prevent the top from accidentally folding up.
- 40 The lower end of the bottom section C' is provided with a bow, pivotally connected at its upper end to the extreme upper ends of the bars E above the pivots D, so as to hold this section properly extended when the other sections are raised and swung forward, as previously explained. The material covering the bow has its side flaps covered with 45 rubber bands C¹⁵, connected to the lower ends of the rods G², the lower edges of said sides extending within the seat-casing B² when the top is extended to prevent rain from driving upon the seat B⁴.
- 50 A friction-roller C¹⁶ is preferably journaled on the inside and middle portion of the lowermost bow C⁵ to ride against one of the guide-arms B⁵ and insure a proper movement of the section C² to and from the seat-casing B².
- 55 It is expressly understood that when the bars E move upward they bodily carry the top along, and when the nut G³ strikes the bearing G⁴ then a swinging motion is given to the top sections C³ to bring the same out 60 from the section C² and to then pull the section C² along—that is, swing it forward to its extended position indicated in Fig. 2. The

lowermost folding section C', by its bow, readily moves into an extended position by its own weight.

The device is very simple and durable in construction, can be readily manipulated by the occupant of the seat, and the top is completely out of sight when folded up into the casing B². As the top forms a fixture of the seat, it can be readily taken off from the wagon-body and placed upon another whenever desired or stored away with the seat.

Having thus fully described my invention, I claim as new and desire to secure by Letters Patent—

1. A vehicle-top, comprising a non-collapsible section mounted to swing, a folding section hung loosely on the lower end of the non-collapsible section, and a second section 85 adapted to swing over the upper end of the said non-collapsible section, substantially as shown and described.

2. A vehicle-top, comprising a non-collapsible section mounted to swing, a folding section hung loosely on the lower end of the non-collapsible section, a second section adapted to swing over the upper end of the said non-collapsible section, and a connection between the top and the middle section, to move the 95 latter into final position by the top section, substantially as shown and described.

3. A vehicle-top having a non-collapsible section mounted to swing, a section connected with the non-collapsible section, and adapted 100 to swing over the same and having a swinging motion independent thereof, and means for raising the top and giving an independent swinging motion to the top section, substantially as shown and described.

4. A device of the class described, provided with bars fitted to slide, means for imparting motion thereto, a non-collapsible middle section hung on the said bars, a top section connected with the said non-collapsible section, 110 crank-arms connected with the outer bow of the top section, rods connected with the said crank-arms, and fixed stops for engaging the rods and limiting their upward sliding motion, to impart movement to the crank-arms 115 for extending the top section and swinging the non-collapsible middle section into final position, substantially as shown and described.

5. A device of the class described, provided with rack-bars mounted to slide up and down, a bow fulcrumed in the said bars, crank-arms extending from the fulcrum ends of the said bars, a rod connected with the said bow, and a stop for limiting the movement of the rod 125 to impart a swinging motion to the bow upon farther upward movement of the bars, substantially as shown and described.

6. A device of the class described, provided with bars fitted to slide, means for imparting motion thereto, a non-collapsible middle section hung on the said bars, a top section connected with the said non-collapsible section, 130 crank-arms connected with the outer bow of

the top section, rods connected with the said crank-arms, fixed stops for engaging the rods and limiting their upward sliding motion, to impart movement to the crank-arms for extending the top section and swinging the non-collapsible middle section into final position, and a lower folding-section hung loosely on the lower end of the non-collapsible section, and having a bow carried by the bars, substantially as shown and described.

7. The combination of a seat-frame, comprising a base and an outer casing, the said frame being adapted to be removably rested on a vehicle, a folding top carried on the seat-frame and capable of folding within said outer casing, and means also carried on the seat-frame by which said top may be manipulated.

8. The combination of a seat-frame comprising a base and an outer casing, the seat-frame being capable of resting removably on a vehicle, and a folding top carried by the seat-frame and capable of folding within the outer casing thereof.

9. The combination of a seat frame or support, a bar movable vertically thereon, a folding top carried by the bar, and means in connection with said top by which to extend the same, such means being also in connection with the seat-frame and serving to extend the top as the bar is moved vertically.

10. The combination of a seat frame or support, a bar vertically movable thereon, a folding top carried by the bar, a crank-arm in connection with the folding top, a rod attached to said arm and extending downwardly, and having sliding connection with the seat-frame, and a bearing on the seat-frame adapted to be engaged by the rod as the rod moves upwardly with the bar, whereby to stop the movement of the rod and throw the crank-arm to extend the said folding top.
